[57] CLAIM

The ornamental design for a tape dispenser, as shown.

DESCRIPTION

FIG. 1 is a side elevational view of a tape dispenser, with lid in the open position, showing my new design;
FIG. 2 is a side elevational view of the side opposite to that shown in FIG. 1 thereof, with the lid in the closed position;
FIG. 3 is a top plan view thereof;
FIG. 4 is a bottom plan view thereof;
FIG. 5 is a front view thereof;
FIG. 6 is a rear view thereof.
